(57) **CLAIM**

The ornamental design for an interactive touch screen display for room management, as shown and described.

DESCRIPTION

The patent or application file contains at least one drawing executed in color. Copies of this patent or patent application publication with color drawing(s) will be provided by the Office upon request and payment of the necessary fee.

FIG. 1 is a bottom front perspective view of an interactive touch screen display for room management, showing the new design in a first green color perimeter glow state; FIG. 2 is a front, first side, top perspective view thereof; FIG. 3 is a front, second side, top perspective view thereof; FIG. 4 is a rear, second side, bottom perspective view thereof;

FIG. 5 is a rear, first side, top perspective view thereof in a second green color perimeter glow state;

FIG. 6 is bottom front perspective view of the interactive touch screen display for room management, showing the new design in a first red color perimeter glow state;

FIG. 7 is a front, first side, top perspective view thereof; FIG. 8 is a front, second side, top perspective view thereof; FIG. 9 is a rear, second side, bottom perspective view thereof; and,

FIG. 10 is a rear, first side, top perspective view thereof in a second red color perimeter glow state.

Color, at portions glowing green or red, is part of the claimed design. The dot-dash broken lines depict the bounds of the claimed design. The broken lines form no part of the claimed design.

1 Claim, 10 Drawing Sheets
